UNITED STATES PATENT OFFICE

148,814

DESIGN FOR A PHOTOGRAPHIC FILM DEVELOPING TANK OR SIMILAR ARTICLE

Thomas G. W. Nevell, Riverside, Conn., assignor to The FR Corporation, New York, N. Y., a corporation of New York

Application June 7, 1947, Serial No. 139,516

Term of patent 14 years

(Cl. D61—1)

To all whom it may concern:

Be it known that I, Thomas G. W. Nevell, a citizen of the United States of America and a resident of Riverside, in the county of Fairfield, State of Connecticut, whose post-office address is 101 Park Avenue, New York city, New York, have invented a new, original, and ornamental Design for a Photographic Film Developing Tank or Similar Article, of which the following is a specification, reference being had to the accompanying drawing, forming a part thereof, in which

Figure 1 is a side elevational view of a photographic film developing tank, with the cover in one position thereon;

Fig. 2 is a side elevational view thereof which shows the cover in another position; and Fig. 3 is a top plan view thereof.

I claim:

The ornamental design for a photographic film developing tank, or similar article, as shown.

THOMAS G. W. NEVELL.
